MATCH PACKAGE

Application filed April 8, 1930. Serial No. 442,753.

This invention relates to an improvement in a package of matches of the form generally known as book matches and has for its object to provide a package which shall be so constructed that the possibility of accident by reason of the package becoming accidentally ignited is avoided.

It is known that many serious accidents have occurred by reason of the fact that the packages of matches in use at the present time are sometimes accidentally ignited during the process of striking a match. The abrasive area or striking surface now provided on the present day form of book match packages is located on the inturned strip at one end of the package and is so positioned that if a match is struck on said surface while the cover flap of the package is open, there is every likelihood of the entire package becoming ignited from the flame of the lighted match.

In many instances also, after a match is struck and while the package is open, the user in shielding the flame of the lit match from the wind with his cupped hands, one of which holds the open package, accidentally brings the package close to the flame of the lighted match with the result that the entire package flares up into flame with serious damage to the hands of the user.

It has been found that the initial cause of many accidents resulting from the sudden and accidental ignition of packages of matches is primarily due to the location of the match-striking surface placed on the package and the position of the matches in the package with respect to such surface. Said surface as it is placed at the present day is so positioned that it permits matches to be struck upon it while the package is open and the matches contained in said package are fully exposed to the possibility of ignition from the lighted match.

One of the objects therefore of this invention is to provide a match package in

which a match striking surface will be so located that regardless of how a match is ignited on said surface, the flame of the ignited match will be prevented from coming into contact with the matches contained in the package by the covering of the package.

A further object of this invention is to provide a match package in which a match-striking surface is incorporated, which surface shall be so located that the package must be held in a certain position to permit ignition of a match through the use of said surface, whereby the matches in the package will be held with their ends furthest from the flame of the match so that the possibility of flame from the ignited match reaching the match heads and accidentally igniting the matches contained in the package is avoided.

A still further object of the invention is to provide a match package wherein the matches contained within the same are held in a different relationship with respect to the outer covering of the package than those of the past have been held.

Through the particular arrangement of the matches and the covering for the same, I provide a match package having a maximum of safety. The package is so constructed that a match cannot be struck until the cover is closed and when the cover is closed, the igniting surface is so positioned with respect to the match heads that it is practically impossible for a flame from the lighted match to reach the heads of the matches and accidentally ignite the package.

With these objects and such other objects as may hereinafter appear, in view, I have devised the particular arrangement of parts hereinabove set forth and more particularly pointed out in the claims appended hereto.

Reference is to be had to the accompanying drawing forming a part hereof in which

Figure 1 is a plan view of my improved

match package with the paper covering of the same spread out flat to disclose the arrangement of the match strip;

5 Figure 2 is a face view of the match strip removed from the package in order to fully disclose its fastening flap;

Figure 3 is a perspective view of the complete match package in closed condition; and

10 Figure 4 is a perspective view showing how the package is held during the process of striking a match.

Throughout the various views of the drawing, similar reference characters designate similar parts.

15 In the embodiment of my invention disclosed in the accompanying drawing, 1 indicates the outer paper covering of the match package. The same consists of an elongated strip of cardboard or of some similar material. The strip 1 is provided with a transverse fold line 2 which divides it into a body portion 3 and a cover flap 4. The body portion 3 is folded inwardly at 5 to provide an inturned fastening flap 6 under which a flap or terminal portion 7 provided on the match strip 8 is held by means of a staple 9. The fastening staple 9 passes through the inturned strip 6, the fastening flap 7 on the match strip and finally, through the body portion 3 of the cover. The match strip 8 is preferably composed of two or more layers 10 and 11 of matches 12, said matches having their heads 13 positioned remote from a striking surface 14 provided on the outer face of the cover flap 4. A similar co-operating striking surface 15 is provided at the end of the inturned strip 6 located remote from the match heads 13.

40 When the cover flap 4 is in its closed position as disclosed in Figures 3 and 4, it will be seen that the striking surface 14 provided on the outer face of the cover flap 4 and the striking surface 15 provided on the outer face of the inturned strip 6, co-operate to form a continuous elongated area of an abrasive material located adjacent to the edge of the package that is situated remote from the match heads 13. Thus, when the package is held for the purpose of striking a match, the heads of the matches are far away from the flame and are fully protected by the covering of the match package. It is not possible to strike a match on the abrasive surface 14 with the match package held open since no support is provided behind the same, while the flap is open. Thus, it is necessary to close the flap 4 to hold the package substantially as shown in Figure 4. In such case, the safety features of my improved structure will be readily apparent. The match heads in the package are not only protected from the flame of the ignited match during the process of lighting the match, but also while the match and package are held in the cupped hands 65 while the cigarette is being lit.

The match strip is so constructed that when placed in the package in the manner disclosed, with the fold in the covering disposed parallel to the longitudinal axis of the match strip, advertising matter appearing on the package is held in the proper position to be easily read by the user of the package.

70 If desired, a supplemental fastening staple 16 may be employed. This staple 16 passes through the lower terminal portion 20 of the match strip at its lower edge and prevents the cover from slipping in back of the matches, thus adding a safety factor to my construction.

75 These and many features of improvement 80 are attained by the structure constituting my invention.

What I claim is:

1. A match package having a cover strip, 85 a match strip held cross-wise on said cover strip and having portions of said cover strip folded over it, said match strip having a continuous base portion extending along the ends of the matches in said strip, means for attaching said base portion to the cover strip, 90 said match strip being provided with a flap extending along the sides of the matches in said strip, and means for attaching said flap to the cover strip.

2. A match package having a cover strip, 95 a match strip extending cross-wise on said cover strip, said match strip having terminal portions at its lower edge and at one of its sides, and means for fastening both of said terminal portions to the cover strip.

100 3. A match package having a cover strip provided with a cover flap foldable relative to the cover strip, a match strip extending cross-wise on said cover strip, said match strip having terminal portions at its lower edge 105 and at one of its sides, staples extending through both of said terminal portions to fasten both of the terminal portions to the cover strip, the staple which extends through the terminal portion at the lower edge of the 110 match strip being located adjacent to the point of fold of the cover flap to prevent the inadvertent entry of the cover flap behind the match strip.

115 4. A match package having a cover strip provided with a cover flap foldable relative to the cover strip, a match strip extending cross-wise on said cover strip, said match strip having terminal portions located at its lower edge and at one of its sides, staples 120 extending through both of said terminal portions to fasten both of the terminal portions to the cover strip, the staple which extends through the terminal portion at the lower edge of the match strip being located adjacent to the point of fold of the cover flap to prevent the inadvertent entry of the cover flap behind the match strip, and a striking surface on the outer face of the cover flap 125 extending along the edge thereof which over-

lies the lower terminal portion on the match strip when the cover flap is folded thereover.

5. A match package having a cover strip, a match strip extending cross-wise on said cover strip, said match strip having terminal portions at its lower edge and at one of its sides, means for fastening both of the terminal portions to the cover strip and a striking surface on the outside of the cover strip extending transversely of the matches in the match strip.

Signed at the city, county and State of New York, this 8th day of April, 1930.

BENJAMIN H. FREEDMAN.
